(57) **CLAIM**

The ornamental design for adjustable beam bracket for door reinforcement, as shown and described.

DESCRIPTION

FIG. 1 is the Configuration 1 top view of the adjustable beam bracket for door reinforcement;

FIG. 2 is the Configuration 1 bottom view;

FIG. 3 is the Configuration 1 front view;

FIG. 4 is the Configuration 1 rear view;

FIG. 5 is the Configuration 1 left side view;

FIG. 6 is the Configuration 1 right side view;

FIG. 7 is the Configuration 1 front and top perspective view;

FIG. 8 is the Configuration 1 rear and top perspective view;

FIG. 9 is the Configuration 1 rear and bottom perspective view; and

FIG. 10 is the Configuration 1 front and bottom perspective view;

FIG. 11 is the Configuration 2 top view of the adjustable beam bracket for door reinforcement;

FIG. 12 is the Configuration 2 bottom view;

FIG. 13 is the Configuration 2 front view;

FIG. 14 is the Configuration 2 rear view; of the adjustable beam bracket for door reinforcement.

FIG. 15 is the Configuration 2 left side view;

FIG. 16 is the Configuration 2 right side view;

FIG. 17 is the Configuration 2 front and top perspective view;

FIG. 18 is the Configuration 2 rear and top perspective view;

FIG. 19 is the Configuration 2 rear and bottom perspective view; and,

FIG. 20 is the Configuration 2 front and bottom perspective view.
